US0D1040479S

(12) United States Design Patent (10) Patent No.: US D1,040,479 S
(45) Date of Patent: * Sep. 3, 2024

(54) SKIRTED LEGGING

(71) Applicant: oGorgeous Inc., Encino, CA (US)

(72) Inventor: Cassey Vinh Ho, Encino, CA (US)

(73) Assignee: oGorgeous Inc., Encino, CA (US)

() Term: 15 Years

(21) Appl. No.: 29/923,321

(22) Filed: Dec. 28, 2023

(51) LOC (14) Cl. 02-02

(52) U.S. Cl. D2/731

(58) Field of Classification Search

USPC D2/742, 851, 735, 731

CPC A41D 1/06; A41D 1/14

(57) CLAIM

The ornamental design for a skirted legging, as shown and described.

DESCRIPTION

FIG. 1 is a front elevation view of a skirted legging in a first configuration;

FIG. 2 is a rear elevation view of the skirted legging of FIG. 1;

FIG. 3 is a left side view of the skirted legging of FIG. 1; FIG. 4 is a right side view of the skirted legging of FIG. 1; FIG. 5 is a top plan view of the skirted legging of FIG. 1; FIG. 6 is a bottom plan view of the skirted legging of FIG. 1;

FIG. 7 is a front elevation view of the skirted legging of FIG. 1 in a second configuration;

FIG. 8 is a rear elevation view of the skirted legging of FIG. 7;

FIG. 9 is a left side view of the skirted legging of FIG. 7; and,

FIG. 10 is a right side view of the skirted legging of FIG. 7. The broken lines showing the torso ankles and feet depict environmental structure and forms no part of the claimed design.

1 Claim, 7 Drawing Sheets
